UNITED STATES PATENT OFFICE

JOSEPH ZAPPULLA, OF BAY SHORE, NEW YORK

DESIGN FOR A HAIR BRUSH

Application filed April 16, 1931. Serial No. 39,498. Term of patent 3½ years.

To all whom it may concern:

Be it known that I, JOSEPH ZAPPULLA, a citizen of United States, residing at Bay Shore, Long Island, in the county of Suffolk and State of New York, have invented a new, original, and ornamental Design for a Hair Brush, of which the following is a specification, reference being had to the accompanying drawings, forming part thereof.

In the drawings:

I claim:

The ornamental design for a hair brush as shown.

JOSEPH ZAPPULLA.
